CLAIM

The ornamental design for a 10-22 recoil buffer, as shown.

DESCRIPTION

FIG. 1 is a front view of the 10-22 recoil buffer showing the unique design of the invention;

FIG. 2 is an end view of the 10-22 recoil buffer;

FIG. 3 is an isometric view showing the 10-22 recoil buffer;

FIG. 4 is a side view of another embodiment of the 10-22 recoil buffer of this design; and,

FIG. 5 is an isometric view of another embodiment of the 10-22 recoil buffer of this design.
